Patented Sept. 5, 1922.

UNITED STATES PATENT OFFICE.

FRANK PERME, SR., OF CLEVELAND, OHIO.

CABINET FOR MUSIC ROLLS.

Application filed February 4, 1921. Serial No. 442,391.

To all whom it may concern:

Be it known that I, FRANK PERME, Senior, a citizen of the United States, and resident of Cleveland, in the county of Cuyahoga and 5 State of Ohio, have invented certain new and useful Improvements in Cabinets for Music Rolls; of which I hereby declare the following to be a full, clear, and exact description, such as will enable others skilled 10 in the art to which it appertains, to make and use the same.

The objects of the invention are to provide an improved form of cabinet for the music rolls of a player piano, and in which a large 15 number of rolls can be stored out of contact with each other and retained in neatly rolled condition, always ready for use.

The invention includes, a cabinet provided with a multiple number of sliding panels, 20 upon both sides of which the music rolls are detachably secured.

These panels can be separately drawn out of the cabinet, and the rolls displayed thereon are immediately accessible for use and for 25 greater convenience the aforesaid panels are also constructed to swing back on their supports.

A further advantage obtained by the use of these sliding panels is the possibility of 30 storing music rolls according to their classes upon separate panels, thus permitting the collection, of different types such as, rolls for religious, popular or classical music, including hymns, dances, sonatas, etc., by 35 themselves, where they can readily be found without confusion or loss of time.

The invention further includes, the combination and arrangement of the various parts, and construction of details, herein- 40 after described, shown in the accompanying drawings and specifically pointed out in the claim.

In the accompanying drawings Fig. 1, is a front elevation of the device, Fig. 2, is a 45 side elevation showing one of the panels upon which the music rolls are stored, drawn out of the case, Fig. 3, is a plan of the cabinet, Fig. 4, is a vertical section enlarged, on line 4-4, Fig. 3, showing one of the hinged 50 sliding panels, Fig. 5, is a similar vertical section on line 5-5, Fig. 3, showing a panel and the spring keepers for the music rolls.

In these views A is the case of the cabinet, B a door hinged thereon, C C, are vertical

panels which are attached by means of hinge 55 leaves D D', to blocks E E, that are slidably movable in the dove-tailed grooves F F, in the top and bottom walls of the cabinet.

These panels when drawn out of the cabinet swing upon pintle pins G G, which connect the pairs of hinge leaves, but when pushed back into the case the edges H H, of the panels enter the grooves and keep the panels in parallel relation to each other. Vertically above each other spring keepers, 65 I I, are secured to the panel walls, on both sides thereof.

In these keepers the music rolls are secured, and the sides of the gripping forks retain the tightly rolled films in place and 70 prevent them from becoming unrolled.

The rolls can also be displayed with their titles in view, and the panels on which they are mounted can be swung from side to side when drawn out of the case thus presenting 75 the rolls in turn to the operator.

The rolls are provided with flanges J J, which rest upon the thin portion of the panels, and against the stiles at the sides of the panel thus preventing them from trust- 80 ing in their supports.

Having described the invention what I claim as new and desire to secure by Letters Patent is;

In a cabinet for music rolls, in combina- 85 tion, a casing, vertical panels transversely slidable therein, the upper and lower walls, of said cabinet provided with transverse grooves, blocks slidable in said grooves, hinge leaves connecting said blocks respec- 90 tively to said panels, said panels comprising each a thin central portion and thicker stiles, so that music rolls provided with flanges may engage said stiles and be retained from longitudinal movement thereby, said panels constructed and arranged to swing free of said 95 grooves when drawn out of said case, but to enter said grooves when pushed into the case, and means for detachably securing said rolls to the vertical faces of said panels, said se- 100 curing means serving also to compress the rolls and maintain them in a closely wound condition.

In testimony whereof, I hereunto set my hand this 25th day of January 1921.

FRANK PERME, SR.

In presence of—

S. W. SANGSTER.
